UNITED STATES PATENT OFFICE.

ARTHUR KITSON AND WILLIAM SMITH HORRY, OF PHILADELPHIA, PENNSYLVANIA, ASSIGNORS, BY DIRECT AND MESNE ASSIGNMENTS, TO THE KITSON GAS LIGHT IMPROVEMENT COMPANY, OF SAME PLACE.

CARBURETING-LAMP.

SPECIFICATION forming part of Letters Patent No. 395,834, dated January 8, 1889.

Application filed October 13, 1886. Serial No. 216,127. (No model.)

To all whom it may concern:

Be it known that we, ARTHUR KITSON and WILLIAM SMITH HORRY, both of the city and county of Philadelphia, and State of Pennsylvania, have invented an Improvement in 5 Carbureting-Lamps, of which the following is a specification.

Our invention has reference to gas-fixtures; and it consists in certain improvements, all 10 of which are fully set forth in the following specification, and shown in the accompanying drawings, which form part thereof. Heretofore gas-fixtures of this class have been made with an extensive heater for the incoming 15 gas arranged above the flame, which heater and gas-pipe were exposed to the atmosphere on all sides and the carbureting-receptacle was located below the gas-burners and detachable, leaving the burners as part of the 20 suspended fixture. It has also been proposed to provide a gas-fixture with a central heater-pipe having a surrounding case and a carbureting-receptacle above the burners and heated thereby. It has also been proposed to 25 suspend shades by means of expansible clamps, but not in connection with a gas-fixture of the nature hereinafter set out.

Our invention has particular reference to a form of fixture set out in our application, 30 Serial No. 202,598, filed May 19, 1886, in which a central gas-pipe is divided longitudinally into spiral passages and surrounded by a heat-arresting case, which, while it heats the gas to a constant degree, prevents over-heating. In that application the said construction is embodied with the employment 35 of a carbureting-receptacle at the bottom of the gas-supply pipe and below the gas-burners. This application is an improvement 40 thereon in the following respects—viz., the carbureting or enriching receptacle is made with the burners rigidly secured to it, whereby, whenever the receptacle is removed for replenishing, the burners must be removed 45 also, and thus their inspection is naturally insured. Gas-burners in fixtures of this class have a tendency to become clogged by the deposition of the carbonaceous deposits from the enriched gas, and it is of the utmost im-

portance to provide means for the proper inspection of said burners—a work which cannot be properly done when the burners are made part of the rigid fixture, as has heretofore been the case. The construction may also be simplified by making the burners 55 rigid with the carbureting-vessel. The construction of the heater-case for arresting the products of combustion is extremely simple, and yet most desirable and ornamental. The gas-regulating valve is arranged at the top of 60 the gas-pipe and protected from heat by an extended shield, which also protects the gas-pipe above the valve from ascending heated products, preventing it acting as a heater in any manner. The shade is held to the fixture 65 by a removable jointed clamp, which encircles the heater-case, and hence may be readily applied to fixtures already erected, and may be adjusted high or low, as desired.

The foregoing improvements enable the 70 fixture to be used with the best effect and with the least care, is cheap to construct, durable in use, not liable to get out of order, and is highly ornamental in appearance.

In the drawings, Figure 1 is a sectional elevation of a gas-fixture embodying our invention. Fig. 2 is a plan view of the burners and carbureting-receptacle removed from the gas-pipe, and Fig. 3 is a perspective view of the adjustable and removable shade-clamp. 75 80

A is the central gas-supply pipe, and is connected at the top to the gas-main section B by a valve, C, having an operating-lever, c. This gas-pipe A is preferably provided with a spiral or twisted ribbon of metal, a, to cause 85 the gas to be divided and insure its being thoroughly circulated and mixed, whereby it is all uniformly heated to a fixed degree.

Surrounding the pipe A at the top and resting against the valve C is a large washer, M, 90 which receives the large circular shield L, the outer part, l, flaring upward and throwing off any ascending products of combustion or heated air and keeping the gas-pipe above the shield cool. The lower part of this shield receives the upper end of the case K, which forms an annular space, k, around the gas-pipe, the top of which is practically or simul- 95

taneously closed. The small leakage at the joint *m*, or from one or more very small holes, *N*, in the top of the casing, would be advantageous in very slowly and gradually causing a change in the heated products in the space *k*. The lower end of the case *K* is centered and held up by bell *O*, which is preferably of much less diameter than the shield *L*. This bell has a shoulder, *O'*, which receives the case *K* and keeps it in place. The upper part of the bell fits snugly around the pipe *A*, and is perforated, as at *o*, to allow ingress to the heated products ascending from the burners. This bell is held up in place by a sleeve, *T*, which surrounds the pipe *A*, and which is clamped upward against said bell by the nut *D* of the coupling for connecting the burners and carbureting-vessel to the gas-pipe *A*. It will now be observed that the fixture from *B* to *D* is all rigidly clamped together by valve *C* and nut *D*, and yet it may be dismantled when desired for repairs. This portion of the fixture is secured to the building by a permanent joint.

The carbureting-vessel *H* is made of light sheet metal spun into shape and permanently secured to the coupling-sleeve *E*. Screwed into the sides of this piece *E* and close to the carburetor are the gas-burner pipes *G*, which radiate from the center and are provided with the burner-tips *g*. From this it will be seen that there is one large central opening, *F*, and a series of small burner-openings from the carburetor. This combined carburetor and burner is detachably secured by the coupling-joint *e* with the nut *D*, and the joint is made gas-tight by a packing-washer, *d*.

J is a small end section of pipe, which may be screwed into the bottom of the gas-pipe *A* and project through the opening *F* into the carburetor, as shown.

By thus making the carburetor rigid with the burners both must be removed together, thereby enabling the burners to be thoroughly inspected and cleaned every time it is required to replenish the carburetor with the carbureting material, which is in practice a crystallized carbon of high volatility. Considerable difficulty has been experienced in attaching shade or shades to fixtures of this class. In some instances shades are not desirable or wanted; but heretofore it has been necessary to secure the holder for the shade rigidly on the fixture, whether the shade was required or not, as otherwise, if a shade were required, the entire fixture would have to be taken apart to put on the holder. In the present construction the globe-holder *P* is made of two parts, *P'*, hinged together at *p* and clamped upon the case *K* by a thumb-screw, *p'*, which draws the parts *P'* together. These parts of the clamp have the hooked arms *P*², which fit into the annular groove *s* of the shade or globe *S* and support it. By this construction the shade may be readily adjusted high or low, as desired. This clamp may be modified in many ways, the detail

thereof being immaterial to our invention, as the essential feature is an adjustable clamp with a fixture of this class, whereby the shade and its clamp may be put on or taken off a fixture when in use. The shade is of such a shape and diameter that it collects and directs the products of combustion up between the annular space formed by the arms of the clamp and shade around the case *K* to protect it against cold-air currents. The form of coupling between the pipe *A* and carburetor may also be modified; hence while we prefer the construction shown the details thereof may be varied without departing from our invention.

We do not herein claim the subject-matter claimed in our application, Serial No. 202,598, filed May 19, 1886.

Having now described our invention, what we claim as new, and desire to secure by Letters Patent, is—

1. A hydrocarbon or carbureting receptacle having the gas-burners permanently secured to it, in combination with the gas-supply pipe and a coupling-joint above the burners, whereby the carbureting-vessel and its burners are detachably connected with the supply-pipe, substantially as and for the purpose specified.

2. In a gas-fixture, the depending gas-pipe having burners at the bottom, a surrounding casing for said pipe closed at the top and having an enlarged mouth at the bottom, a clamp to surround and grip said casing, and a shade supported by said clamp, but forming an annular opening through its top, whereby the products of combustion are guided up around the casing and protect it from the action of cold-air currents, substantially as and for the purpose specified.

3. In a gas-fixture, the depending gas-pipe, a surrounding case to arrest and hold products of combustion to heat the incoming gas, the said case having a bell-shaped or flaring mouth at the bottom, a gas-burner at the bottom, a clamp adapted to surround the case and grip the same, and a shade held or supported by said clamp, whereby the shade and its clamps may be put upon a fixture already erected without dismantling the same.

4. In a gas-fixture, the depending gas-pipe, a surrounding case to arrest and hold products of combustion to heat the incoming gas, the said case having a bell-shaped or flaring mouth at the bottom and an enlargement of the top, a gas-burner at the bottom, a removable jointed clamp adapted to surround the case and grip the same, and a shade held or supported by said clamp, whereby the shade and its clamps may be put upon a fixture already erected without dismantling the same, substantially as and for the purpose specified.

5. In a gas-fixture, the combination of central gas-pipe, *A*, the surrounding heater-case *K*, forming an annular chamber, *k*, around the gas-pipe, the centering-shield *L* at the top to practically close said case *K* at the upper end, the centering-bell *O* at the bottom, having

openings or perforations to support the case K and admit heated products thereto, the sleeve T, to support the bell O, suitable burners and a carbureting-receptacle rigidly secured together and detachably connected to the bottom of the gas-pipe, and a nut to hold said sleeve in place, the construction admitting of ready dismantling or putting of the parts together.

6. In a gas-fixture, the combination of central gas-pipe, A, the surrounding heater-case K, forming an annular chamber, k, around the gas-pipe, the centering-shield L at the top to practically close said case K at the upper end, the valve C at the upper end of pipe A, the body of which is adapted to hold shield L down, the centering-bell O at the bottom, having openings or perforations to support the case K and admit heated products thereto, the sleeve T, to support the bell O, suitable

burners at the bottom of the gas-pipe, and a nut to hold said sleeve in place, the construction admitting of ready dismantling or putting of the parts together.

7. In a chandelier, a gas-supply tube above the burner having its interior divided into two longitudinal spiral or circuitous passage-ways, in combination with an inlet at one end connecting with both of said passage-ways and a gas-burner at the other end in like connection with both passage-ways, substantially as and for the purpose specified.

In testimony of which invention we hereunto set our hands.

ARTHUR KITSON.
WILLIAM SMITH HORRY.
